UNITED STATES PATENT OFFICE.

JOHN A. MATONSEK, OF CLEVELAND, OHIO.

GAS EXTINGUISHER AND LIGHTER.

No. 928,776.

Specification of Letters Patent.

Patented July 20, 1909.

Application filed July 22, 1908. Serial No. 444,845.

To all whom it may concern:

Be it known that I, JOHN A. MATONSEK, a citizen of the United States, residing at Cleveland, in the county of Cuyahoga and State of Ohio, have invented new and useful Improvements in Gas Extinguishers and Lighters, of which the following is a specification:

This invention relates to means for lighting and extinguishing gas burners, the object of the invention being to provide simple electrically controlled apparatus for accomplishing the result referred to, the mere pressure of an electric button or circuit closer operating at one time to light the burner and the succeeding time to extinguish the light.

A further object of the invention is to provide means for regulating the size of the flame of the initial or pilot burner; also means for increasing the supply of gas to the pilot burner, whereby the flame is caused to flare up or increase in size in order to insure the proper ignition of the gas flowing through the main passage of the burner.

With the above and other objects in view, the nature of which will more fully appear as the description proceeds, the invention consists in the novel construction, combination and arrangement of parts as herein fully described, illustrated and claimed.

In the accompanying drawings:—Figure 1 is a side elevation of a burner showing the improved apparatus applied thereto, illustrating the normal position or position of rest of the operative parts of the mechanism. Fig. 2 is a similar view showing the position of the parts when the circuit is closed. Fig. 3 is a horizontal section on an enlarged scale through the plunger valve casing. Fig. 4 is a detail elevation showing the pawl and ratchet mechanism for preventing a driving movement of the valve stem.

Referring to the drawings, 1 designates a gas burner which may be of any usual or preferred form, 2 designating the tubular base of the burner and 3 the gas supply pipe which leads through the base of the burner. 4 designates the valve chamber in which is mounted a gas cut off valve, the stem of which is indicated at 5 by dotted lines in Figs. 1 and 2 and by full lines in Fig. 4.

Mounted fast on one end of the valve stem 5 is a ratchet wheel 6 having a certain number of teeth 7, four being shown by preference. Co-operating with the ratchet wheel

5 is a spring-pressed detent 8 which acts in connection with the ratchet wheel to prevent the stem 5 from turning backward. Fast on the opposite end of the stem 5 is a spider or in other words a series of radiating arms 9 each of which carries at its outer end a laterally projecting pin 10 adapted to be operated upon by a main valve operating lever 11 which is fulcrumed at its outer end 12 on a bracket arm 13 extending laterally away from the valve casing 4, as shown in Figs. 1 and 2. Connected pivotally to the free end of the lever 11 is a rocking finger 14 which is held in a normally projecting position as shown in Fig. 1 by means of a spring 15, which, however, yields to allow the extreme point of the finger to rock downward as the lever 11 swings upward under the influence of a lever-elevating spring 16 which is coiled around the journal or pivot 12 of said lever and has one arm connected to the lever while the other arm is connected to the bracket 13. The lever 12 is further provided with an arcuate slot 17 in which works a pin 18 carried by the upper end of a second pilot valve operating lever 19 which is fulcrumed at the point 20 intermediate its ends on the lower end of a slotted guide 21 fastened to the bracket 13 and extending upward over the lever 11 to limit the upward movement of said lever or in other words stop said lever when it reaches the point illustrated in Fig. 1. On the opposite side of the fulcrum 20 the lever 19 is provided with a foot extension 22 which is movable into and out of contact with the projecting end of the stem 23 of a plunger valve 24 movable lengthwise of a valve chamber 25 at one side of the base 2 of the burner and communicating with the main gas supply pipe 3 by means of a passage 26 which leads directly into the plunger valve chamber 27.

28 designates a pilot tube the discharge end of which is arranged close to the main burner so as to readily ignite the gas in said burner, the opposite end of said pipe being attached to the base of the burner and communicating with the second gas passage 29 which leads into the plunger valve casing 27 as shown in Fig. 3. A relatively smaller communicating passage 30 extends from the gas passage 26 to the other passage 29 and is controlled by a regulating screw 31 as shown in Fig. 3, thereby permitting any desired amount of gas to flow through the

passage 30 from the inlet passage 26 to the passage 29. It will further be observed that the larger portion of the plunger valve or in other words the valve proper 24 normally obstructs the entrance to the outlet passage 29, being held in that position by means of a valve closing spring 32 which acts in a direction to cause a projection of the stem 23 from the casing 25 so that said stem may be acted upon by the foot extension 22 of the valve operating lever 19.

33 designates a solenoid or magnet comprising a longitudinally movable core 34 from which a suitable connection 35 extends to the lever 11 for imparting motion to said lever or in other words, drawing the lever down when the solenoid is energized. The solenoid 33 is shown as mounted upon a suitable base 36 provided with binding posts 37 to receive the current wires of a circuit including a generator or battery and a push button or circuit closer, (not shown).

From the foregoing description it will be apparent that when the solenoid is energized by closing the circuit, the core 34 is drawn backward, thus swinging the lever 11. This causes the pivoted finger 14 to come in contact with one of the pins 10 of the spider and depress the arm from which said pin projects, moving the stem 5 of the main supply valve a one-fourth of a revolution which has the effect of opening or closing said valve as the case may be. As the finger 14 swings downward, a heel projection 38 on the extension 22 swings upward and engages beneath the pin 10 thereby arresting the movement of the spider at the point shown in Fig. 2 after it has moved 90°. When the circuit closer is released and the circuit broken, the spring 16 acts to move the lever 11 upward to the position shown in Fig. 1, thereby restoring all parts of the mechanism to their normal position of rest, as shown in Fig. 1. Thus, each time the circuit is closed a one-fourth of a revolution is imparted to the main supply valve, thus turning on and shutting off gas alternately. At the same time the plunger valve 24 is operated which admits an additional supply of gas to the pilot tube 24 causing the flame at the discharge end thereof which is always lighted to flare up, thus insuring the ignition

of the gas at the main burner when the main burner valve is opened.

I claim:—

1. In a device of the class described, the combination of a main burner, a main burner supply valve, a main valve operating lever, a solenoid connected with said lever and adapted to swing said lever when the solenoid is energized, a pilot tube, a plunger valve controlling the supply of gas to said pilot tube, and a second lever operatively connected to the first named lever and adapted to operate said plunger valve simultaneously with the operation of the main burner supply valve.

2. In a device of the class described, the combination of a main burner, a main burner supply valve, a series of arms projecting radially from the stem of said valve, a main valve operating lever; a solenoid connected with said lever and adapted to swing said lever when the solenoid is energized, a pilot tube, a plunger valve controlling the supply of gas to said pilot tube, and a second lever operatively connected to the first named lever and adapted to operate said plunger valve simultaneously with the operation of the main burner supply valve, substantially as described.

3. In a device of the class described, the combination of a burner, a main burner supply valve, a pilot light tube, a spring closed plunger valve controlling the gas supply of said pilot light tube, a main valve operating lever, a pivoted finger carried by said lever, a series of arms radiating from the stem of the main burner supply valve and adapted to be operated upon by said finger, the finger being mounted to snap past the arms in the return movement of the main valve operating lever, a pilot valve operating lever connected with the main valve operating lever and adapted to coöperate with the plunger valve to open the latter, and a solenoid connected with one of said levers, substantially as described.

In testimony whereof I affix my signature in presence of two witnesses.

JOHN A. MATONSEK.
